VOTING MACHINE

Ransom F. Shoup, Ardmore, Pa., assignor to The
Shoup Voting Machine Corporation, Philadelphia, Pa., a corporation of Delaware

Application January 18, 1940, Serial No. 314,384

2 Claims. (Cl. 308—22)

This invention relates to voting machines and more especially to a voting machine of the general type illustrated in the patent to Shoup et al. No. 2,054,102 and this application is a continuation in part of Serial No. 126,575.

In voting machines of this type, rotatable spindles equipped with handles are provided for actuation by a voter to register his vote. These spindles are provided with means for co-operation with other elements of the machine to control the operation of the machine and to condition the machine for different types of voting.

An object of this invention is a spindle assembly and support which may be readily incorporated in a voting machine when originally constructed and which may be easily and quickly supplied with additional members for conditioning the machine for different voting conditions.

Other objects, novel features and advantages of this invention will become apparent from the following specification and accompanying drawings, wherein:

Fig. 1 is a fragmentary horizontal section substantially on the line 1—1 of Fig. 2 of a voting machine embodying the invention;

Fig. 2 is a section on the line 2—2 of Fig. 1, partially broken away with additional elements mounted on the spindles;

Fig. 3 is a section on the line 3—3 of Fig. 1;

Fig. 4 is a section on the line 4—4 of Fig. 1;

Fig. 5 is a fragmentary rear view of Fig. 1, partially broken away;

Figs. 6 and 7 are similar sections on the line 6—6 of Fig. 2 with the elements in different positions;

Figs. 8 and 9 are similar sections on the line 8—8 of Fig. 2 with the elements in different positions, and

Fig. 10 is a perspective view of a spindle assembly.

In so far as possible, the reference characters used in the following specification will correspond to the reference characters used in the specification of said Patent No. 2,054,102 and said application, Ser. No. 126,575. Only the parts actually constituting part of the present invention will be described in detail, reference being had to said patent and application for disclosure of the other details of the machine.

A plurality of columns of spindles 38 are journaled in a partition 30a and in straps suspended from a cross-plate 41 to which each strap is detachably connected by a bolt 41a. Each strap is composed of two parts 40' and 40'' which are held in assembled relation by the bolt 41a. Each

spindle 38 is equipped with an operating handle 30 and is of square cross-section except that it is provided with a circular groove 38a to be received in a circular bearing provided therefor in the strap 40 and additional circular grooves, the purpose of which will later become apparent. Each part of the strap 40 is provided with a series of generally circular apertures 40a of sufficient diameter to permit passage of the square portion of the spindle and a connecting semi-circular aperture 40b of the same diameter as the circular portion 38a (Fig. 5). The arrangement of the apertures 40a and 40b in one part of the strap 40 is just the reverse of the arrangement in the other part of the strap so that by proper arrangement of the two parts of the strap either the apertures 40a or 40b may be brought into coaxial relation. Each strap part has a hole into which extends the bolt 41a and the relation of said bolt holes to the apertures 40a and 40b is such that when the bolt holes are in coaxial relation, the apertures 40b of one strap section are in coaxial relation with the apertures 40b of the other strap section. When the two parts of the strap 40 are positioned with the apertures 40a in coaxial relation, a spindle may be passed therethrough to bring the groove 38a into alignment with the strap and then the parts moved to bring the apertures 40b into coaxial relation around the circular portion 38a, thereby forming a bearing therefor and locking the spindle against axial movement.

The assembly of the spindles in the straps is accomplished with the straps disconnected from the cross plate 41 and with the strap sections disconnected from each other. The strap sections are placed relative to each other so that the apertures 40a of one strap section are in register with the apertures of the other strap section, after which the spindles 38 are inserted through both spindles until the circular portions 38a lie in alignment with the strap sections. Next, the strap sections are moved relative to each other and relative to the spindles to bring the apertures 40b of one strap into register with the apertures 40b of the other strap, in enclosing relationship to the circular portions 38a. With the strap sections in this relationship, the bolt holes at the upper ends thereof are in register and the straps are then fastened together and to the plate 41 by insertion of the bolt 41a into them.

Each spindle 38 extends through and supports a channel member 60, the ends of which engage the partition 30a and a strap 40 and the chan-

nel member is received within square apertures in two arms 59 and 59'. The arms 59 and 59' on successive vertical spindles are offset so as not to interfere with each other. A rod 59b extends between and has its ends attached to the arms 59 and 59'. Some of the rods 59 are attached to pull straps 61 leading to an interlock (not shown). A plate 59a is attached to each arm 59' through the intermediary of the rod 59b which passes through a slot in the plate. The plate is thus slidably and rotatably connected to the arm and is, therefore, capable of being adjusted to different positions relative to the plate as fully described in Serial No. 126,575. Shoulders 60a are provided on the channel member for locating the arms 59 and 59' on such member and the arms are held against the shoulders 60a by the rod 59b. By reason of the rectangular cross-section of the channel member and its snug fit on the square portion of the spindle, it is firmly secured to the spindle and rotates therewith. Likewise, rotation of the spindle causes rotation of the arms 59 and 59'. The arms 59 co-operate with a locking and restoring frame 65 as described in said Patent No. 2,054,102 and the arms 59' and plates 59a co-operate with vertically movable members 190 in the manner described in said Shoup application, Serial No. 126,575.

A counter C is associated with each spindle 38 and is provided with a drive pinion 43 having a square aperture through which extends the square portion of a spindle 38 so that the pinion is fixed to the spindle. The counter preferably is of the construction disclosed and claimed in Shoup Patent No. 2,140,336.

For certain voting requirements, it is necessary to connect at least some of the spindles to an additional interlock of the pull strap type. For this purpose, each spindle is provided with a circular groove 38b. On each spindle which is to be connected to the additional interlock is mounted an arm 75 having a square aperture of proper size snugly to receive the square portion of a spindle 38 (Figs. 6 and 7). A plate 76 is rotatably connected to the arm and carries a coaxial cylindrical stud 77 at the outer end of which is provided a substantially triangular shoulder 78 projecting from the stud periphery. The axis of the stud and the plate lies in the extension of a diagonal of the arm aperture. The plate 76 is substantially circular in shape with a projecting arm 79 and the diameter of the circular portion of the plate is greater than the distance from its axis to the nearest corner of the square aperture and in the periphery of the plate is provided a notch 80. The arm is placed on a spindle by first orienting the plate 76 to bring the notch 80 into register with the corner of the apertures so as to permit passage of the square portion of the spindle therethrough. After the arm is located on the spindle with the plate 76 in alinement with a groove 38b, the plate 76 is rotated to enter the groove 38b and lock the arm against movement axially of the spindle, the extent of rotation being limited by engagement of the extension 79 with the spindle. An interlock strap 61' is formed at its end with an aperture of proper size and shape to pass over the shoulder 78. Such strap normally extends horizontally and can readily be assembled over the stud 77 when the latter is in the position shown in Fig. 5. Upon rotation of the plate 76 to the position

shown in Fig. 6, the shoulder 78 moves out of register with the aperture thereby securely fastening the strap to the stud.

For certain voting requirements, it is necessary to interconnect a plurality of spindles either in a horizontal row or a vertical column by means of a bar or rod.

Figs. 8 and 9 illustrate an arrangement for attaching either vertical or horizontal bars to the spindles to meet such requirements. Two arms 81 and 82 have square apertures of proper size snugly to receive the square portion of a spindle 38 and the apertures are so arranged that they register with each other only when arms 80 and 81 are oriented with respect to each other and are out of register when the arms are in register. The arms 80 and 81 are provided respectively with apertures 83 and 84, one of which preferably is tapped. To mount the arms on a spindle, they are arranged as shown in Fig. 8 with the apertures in register as shown in Fig. 8, and then are moved along the spindle until one arm is in alinement with a circular groove 38c of the spindle. This arm is then rotated to bring it into register with the other arm, thereby causing its sides to be misaligned with the sides of the spindle, thereby locking it against axial movement (Fig. 9). A stud 85 passing through a bore also passes through the apertures 83 and 84 to retain the arms in register. With this arrangement, one arm locks the assembly against axial movement and the other arm attaches the assembly to the spindle for rotation therewith. A horizontal or vertical bar 86 is connected to each assembly by the stud 85 thereby interconnecting a plurality of spindles. The arms 81 and 82 may be in contact with each other and the bar 86 rests upon one arm or the bar 86 may be arranged between the two arms, both of these arrangements being illustrated in Fig. 2.

I claim:

1. In a voting machine, a spindle of square cross-section having a circular portion of less diameter than the spindle width, supporting members in which said spindle is journaled, a pair of identical plates having square apertures of proper size snugly to fit said spindle, said apertures being concentric but differently oriented, and means to attach said plates together in registration with one plate aligned with said circular portion and with the corners of the square section of the spindle overlying the sides of said plate aperture.
2. In a voting machine, a spindle having a circular portion terminating at each edge in portions of greater cross-section than said circular portion, a two-part supporting member with each part having an opening for receiving said spindle, said openings being identical in shape but oppositely arranged and each opening including an arcuate portion of proper size snugly to receive one-half of the circular portion of said spindle with the two portions so related as to completely encircle the cylindrical portion of the spindle and a second arcuate portion of sufficient size to receive said larger cross-section portions of the spindle with the two second arcuate portions so related as to be misaligned when the first two arcuate portions are in circle-forming relation, and means for releasably supporting said two supporting member parts with said first arcuate portions in circle-forming relation.

RANSOM F. SHOUP.
